UNITED STATES PATENT OFFICE.

ALFRED A. FREELAND, OF NEW YORK, N. Y., ASSIGNOR OF ONE-HALF TO
FRANCIS DEIMEL, OF SAME PLACE.

SMOKE-CONSUMING APPARATUS.

SPECIFICATION forming part of Letters Patent No. 589,169, dated August 31, 1897.

Application filed April 6, 1897. Serial No. 630,955. (No model.)

To all whom it may concern:

Be it known that I, ALFRED A. FREELAND, a resident of the city, county, and State of New York, have invented certain new and useful Improvements in Smoke-Consuming Apparatus, of which the following is a specification.

My invention relates to smoke-consuming apparatus, and has for its object to produce a simple efficiently-operating device for consuming smoke.

My invention will be understood by referring to the accompanying drawings, showing an embodiment of my invention.

15 In the drawings, Figure 1 is a front elevation of my smoke-consuming apparatus. Fig. 2 is an enlarged detail sectional view of the cataract for operating the steam-inlet and the damper. Fig. 3 is a broken-away plan view 20 of the steam and air distributor; and Fig. 4 is a section on line 4 4 thereof, showing the means for adjusting the disburser of the said steam and air distributor to different degrees of inclination corresponding with the requirements of practice.

In the drawings, A is a furnace or boiler provided with any usual ash and furnace doors B C and exit-pipe D. A weighted damper E controls the exit-pipe and is itself 30 controlled by a cord or band or chain, &c., F, connected to the said damper E and operated by the cataract G, to which it is secured by the stem g. Leading from the boiler-dome or other source of dry-steam supply is a pipe H, 35 provided with a check-valve h, (see Fig. 2,) under control of the cataract, as will be described. This pipe H continues to the front of the furnace to the point h', where it may branch, one branch h² entering the funnel h³ 40 in the face of the furnace and the other branch h⁴ entering the funnel h⁵ in the face of the furnace.

The furnace-door C is provided with a spindle c, turning therewith and carrying an arm c' at its upper end, which is suitably connected, as by means of a link c², with an elbow-lever g', (see Figs. 1 and 2,) pivoted upon a bracket g² of the cataract, so that when the door is opened it will radiate its spindle c and 45 cause the arm c' to pull upon the link c² and swing the elbow-lever g' so as to operate the

cataract. The pipes or branches h' enter a header h⁶ by the nipple h⁷, which header is provided with a number of outlets or nozzles h⁸, which discharge into a chambered funnel 55 or disburser J. This funnel or disburser is mounted upon plates j, which are pivotally secured to the funnel-casing h³, as will clearly appear by an inspection of Figs. 3 and 4.

The disburser J is provided with a series of 60 radiating passages j², which serve to disburse or distribute the steam-and-air mixture to the fire, for it will be obvious that as the rear ends of the funnel-casings h³ h⁵ are open to the air the influx of steam from the header will cause 65 an inrush of air through the said funnel-casings, which air will be mixed with the steam and the mixture projected into the fire-box of the furnace. The form of cataract shown in the drawings comprises a cylinder g⁸, in which 70 a chambered piston g⁴ works, which chambered piston is shown as provided with packing g⁵ and a stem g. The chamber of the piston may be suitably loaded, as with lead, shot, or mercury. The stem of the piston g is provided with a cam g⁶ and a stud g⁷. The stud g⁷ is in such position as to be struck by the arm g⁸ of the elbow-lever g'. This arm g⁸ is provided at its end with a cam g⁹, upon which the stud g⁷ rides. The stem of the valve h is 75 connected at its lower end to a valve-operating lever g¹⁰, which is pivoted on the cataract-casing at g¹¹, and is provided at its free end with a bowl g¹², adapted to ride on the cam g⁶, so that the said cam will when the stem is 80 moved rock the said valve-operating lever g¹⁰ so as to pull the valve downward to allow steam to flow through the pipe H into the furnace. 85

The lower end of the cylinder g⁸ is apertured, as with an aperture g¹³, which aperture within the casing is surrounded by a series of valve-supporting points or studs g¹⁴. Resting upon these points or studs is a loose valve g¹⁵, having a guide g¹⁶ projecting into the aperture g¹³. This valve is freely movable up and down, as will be explained.

Having described the construction and operations of the component parts of the structure, I will now proceed to give the operations 100 of the structure in detail.

It will be understood that my apparatus is

intended to operate to distribute steam and air to the fire in the furnace A when a fresh supply of coal is thrown upon the said fire, so as to cause the fire to fully consume the smoke incident to such piling on of coal, which supply, however, need only be kept up for a short time. When the fire-door C is opened to allow coal to be thrown upon the fire, it thereby swings its pintle c, pulling upon the rod c² and swinging the elbow-lever g' on its pivot, thereby bringing the arm g⁸ thereof against the stud g⁷ on the stem of the piston and raising the said piston, and as the piston is raised suddenly the influx of air through the aperture g¹³ in the cataract-casing will cause the valve g¹⁵ to rise, thereby allowing the air to rapidly flow into the cylinder. The rise of the piston also brings the cam g⁶ against the bowl g¹², rocking the lever g¹⁰ and opening the valve h, which valve is kept open by the bowl g¹², resting against the plane face of the cam g⁶, while the piston is raised. This opening of the valve allows steam to pass to the distributors, where it is mixed with air and disbursed over the fire, as explained. The rising of the stem g also permits the weighted damper to close. As soon as the furnace-door is shut the rod c² is thereby forced to the left and swings the elbow-lever g' to its original position, thereby leaving the piston free to descend, which descent will be slow by reason of the fact that the valve g¹⁵ drops upon the points or studs g¹⁴, so that air can only escape between the said valve and the spaces between the points. As the piston slowly descends the valve will be held open and will not be closed until the bowl g¹² rides upon the curved portion of the cam g⁶, when the steam-pressure will close the said valve h as the piston g⁴ reaches its normal position, when the damper will be opened through the medium of its connection F.

It will thus be obvious that for a short time after the closing of the furnace-door the furnace will be supplied with steam and air, which, by the action of the cataract, will be automatically shut off after it has flowed for a predetermined length of time, which is readily arranged by weighting the cataract-piston and limiting the size of the air-exits of the valve.

It will further be obvious that since the joints j of the disburser are friction-joints the said disburser may be adjusted to throw the steam and air in a curtain at various inclinations by inserting a bar into the disburser and prying the said disburser to turn it on its pivot.

62 What I claim, and desire to secure by Letters Patent, is—

1. In a smoke-consuming apparatus, the combination of air and steam supply devices, of a cataract and an operating device therefor, comprising an elbow-lever g' provided with an arm g⁸ in operative relation to the piston of said cataract but disconnected therefrom. 65

2. In a smoke-consuming apparatus, the combination of a valved steam-supply device, a controlling mechanism therefor comprising a cataract, and valve-operating mechanism for operating the steam-valve, and a cam-lever operating on the cataract but disconnected therefrom, so that the said cataract may be operated and the cam-lever returned to its 75 original position, allowing the cataract to perform its function.

3. In a smoke-consuming apparatus, the combination of a valved steam-supply, a valve-operating lever, a piston, a cam-lever 80 for operating said piston, and a cam moved by the said piston and operating the valve-operating lever, substantially as described.

4. In a smoke-consuming apparatus, the combination of a steam-controlling valve, and means for operating the same, comprising a piston, a cam g⁶ moved by the said piston, a valve-operating lever g¹⁰, and a cam-lever for moving the piston, all of the said parts being disconnected from each other so as to be movable independently of each other at predetermined times. 85

5. In a smoke-consuming apparatus, the combination of a steam-regulating valve II, an operating-lever g¹⁰ therefor, a piston, a cam g⁶ moved by the said piston and operating to swing the lever g¹⁰, and a cam-lever g⁸ for operating the piston combined with a connection with the furnace-door, substantially as described. 95

6. In a smoke-consuming apparatus, the combination of an air-inlet chamber or funnel h³, a header therein provided with nozzles, a steam-supply pipe for bringing steam to the header, and a steam-disbursing apparatus 105 having radiating passages located beyond the header and adapted to spread the mixed steam and air in a curtain over the fire.

7. In a smoke-consuming apparatus, the combination of an air-inlet chamber or funnel h³, a steam-inlet device located in the funnel and adapted to draw air into the funnel, and a disbursing apparatus located beyond the funnel and adapted to distribute the mixed steam and air over the fire, the said disbursing apparatus being pivotally mounted so as to be adjustable, substantially as described. 110
